UNITED STATES PATENT OFFICE.

THOMAS L. COOK, OF LOGAN, OKLAHOMA

WHEEL.

1,075,241.

Specification of Letters Patent.

Patented Oct. 7, 1913.

Application filed May 7, 1913. Serial No. 766,161.

To all whom it may concern:

Be it known that I, THOMAS L. COOK, a citizen of the United States, residing at Logan, in the county of Beaver and State of Oklahoma, have invented certain new and useful Improvements in Wheels, of which the following is a specification, reference being had to the accompanying drawings.

This invention relates to new and useful improvements in wheels, and relates more particularly to spring wheels for automobiles, the object of the invention being to provide a spring wheel of the above character which will eliminate the shock and jar of the body of the vehicle when passing over rough and uneven roads.

Another object of the invention is to provide a spring wheel of the above character which will possess advantages in points of efficiency and durability, is inexpensive to manufacture, and at the same time is simple in construction and operation.

With the above and other objects in view, this invention consists in the novel features of construction and the combination and arrangement of parts hereinafter more fully described, pointed out in the claims, and illustrated in the accompanying drawings, in which

Figure 1 is a side elevation of a wheel constructed in accordance with my invention, parts of the same being broken away; Fig. 2 is a longitudinal sectional view taken through one of the spokes; Fig. 3 is a detail sectional view taken through one of the guard members illustrating the application of the same; Fig. 4 is a side elevation of the hub, parts being broken away to illustrate the application of the V-shaped spring; Fig. 5 is a transverse sectional view through the hub.

Referring more particularly to the drawings, 1 indicates the hub of the wheel, to each side of which are secured the plates 3 forming an annular groove 2. The spokes consist of inner and outer sections, the inner sections 4 having their inner ends arranged between the plates 3 and slidably secured by means of the bolts 5 engaging slots 5'. The inner sections 4 of the spokes are tubular in form and provided with an inner closed end 6, while the outer ends of the sections 4 are truncated, as shown at 7, and arranged in spaced relation with the felly 8. The outer sections 9 of the spokes are solid in cross section and are slidably mounted within the

inner sections 4. The outer ends of the outer sections of the spokes are arranged within the recesses 10 formed in the felly 8, and slidably secured by means of the bolts 60 11 engaging slots 11'.

Coil springs 12 are arranged within the inner end of the inner sections 4 and adapted to be disposed between the closed end 6 and the sections 9. Suitable coil springs 13 65 are mounted upon the sections 9 and disposed between the felly and the outer end of the inner sections 4. A plurality of plates 14 are secured to the inner side of the felly 8 and adapted to encircle the outer 70 sections 9 of the spokes and close the recesses 10. From this it will be apparent that the outer ends of the coil springs 13 abut against the plate 14.

Arranged between the spokes at the inner ends thereof are a plurality of V-shaped springs 15, the intermediate portions of which are arranged within the groove 2 of the hub and securely held in position by means of the cross pins 16. The outer ends 75 of the springs 15 are secured to the inner sections 4 of the spokes by means of the metallic bands 17, said bands being provided at their ends with outwardly projecting ears in which are removably arranged the bolts 80 18, which securely clamp the bands to the spokes and hold the ends of the springs 15 in position.

The springs 13 mounted upon the outer sections 9 are provided with guard members 90 19, the outer ends of which are provided with outwardly projecting annular flanges 20 which are loosely secured by means of the screws 21 to the inner face of the felly 8. It will be readily apparent that any 95 suitable means may be used for securing the guard members in position. The inner ends of the guard members 19 engage over the outer ends of the inner sections 4 so as to entirely inclose the springs 13 and prevent 100 mud or other dirt from interfering with the action of the springs.

From the above description taken in connection with the accompanying drawings, it will be apparent that I have provided a 105 simple and durable spring wheel which is adapted for use on automobiles and like vehicles, and which will eliminate all shock or jar from the body of the vehicle when passing over rough and uneven roads. It 110 will be apparent that all shock will be taken up by the springs 13 and 12 so that no jar

will be conveyed to the body of the vehicle. It will also be obvious that the spokes of the wheel are so mounted that they are not only permitted a longitudinal movement 5 but a slight circumferential movement is permitted by means of the slots 5' and 11' in which the bolts 5 and 11 are adapted to work.

It will also be apparent that my device 10 is extremely simple in construction and can be manufactured at a comparatively low cost.

While I have shown and described the 15 preferred form of my invention, it will be obvious that various changes in the details of construction and in the proportions may be resorted to for successfully carrying my invention into practice without sacrificing any of the novel features or departing from 20 the scope of the appended claims.

What I claim is:—

1. A wheel including a hub provided with an annular groove to form spaced side walls, radial sectional spokes having their inner 25 ends loosely secured between said walls, a felly having a plurality of recesses in which the outer ends of the spokes are pivotally secured, plates secured to the inner side of the felly and encircling the outer sections 30 of the spokes, coil springs mounted upon the outer sections of the spokes, and disposed between the outer ends of the inner sections and said plates, and a guard member adapted to inclose said springs and hav- 35 ing an annular flange formed upon the outer end thereof adapted to be loosely secured to the inner side of the felly, said guard

having its inner end mounted upon the outer end of the inner sections of the spokes to entirely inclose said springs, as and for the purpose set forth.

2. A wheel including a hub having an 40 annular groove forming spaced side walls, a plurality of sectional spokes having their inner ends loosely secured between said side walls, V-shaped springs arranged between the inner ends of the spokes, said springs 45 having their intermediate portions arranged between the side walls, securing pins arranged across the groove in the hub to hold the springs in position, clamping members 50 removably securing the ends of the springs to the spokes, a felly having a plurality of recesses in which the outer ends of the spokes are to be secured, plates secured to the felly and adapted to encircle the outer 55 ends of the spokes, coil springs mounted upon the outer sections of the spokes and disposed between the outer ends of the inner sections and the plates, a guard member having an annular flange formed upon the outer end and adapted to be loosely secured 60 to the felly, the inner end of said guard member being movably mounted upon the outer end of the inner section to entirely inclose the coil spring upon the outer section.

65 In testimony whereof I hereunto affix my signature in the presence of two witnesses.

THOMAS L. COOK.
